UNITED STATES PATENT OFFICE

JULIUS D. HAYNSWORTH, OF MINNEAPOLIS, MINNESOTA, ASSIGNOR TO MCQUAY RADIATOR CORPORATION, OF MINNEAPOLIS, MINNESOTA, A CORPORATION OF DELAWARE

ROTOR

Application filed November 18, 1929. Serial No. 407,933.

My present invention has for its object the provision of an extremely simple and highly efficient rotor having laterally projecting blades or wings, and, generally stated, the invention consists of the novel devices and combinations of devices hereinafter described and defined in the claims.

The invention, while capable of more general use, has been especially designed as a fan rotor for blowers and the like.

In the accompanying drawings, which illustrate the invention, like characters indicate like parts throughout the several views.

Referring to the drawings:

Fig. 1 is a face view showing one form of the invention;

Fig. 2 is a view partly in elevation and partly in section taken on the line 2—2 of Fig. 1;

Fig. 3 is a perspective view of the inner unit removed from the rotor; and

Fig. 4 is a face view of the blank from which the inner unit is formed.

For the sake of convenience, the invention will hereinafter be referred to as a fan rotor, and which rotor is made up of one or more units, each formed from a single sheet of material. In the drawings, the fan rotor illustrated comprises two substantially duplicate inner and outer units, each of which includes a flat body member 5 having an axial passageway 6 and circumferentially spaced laterally projecting blades or wings 7 formed on the faces of peripheral teeth 8 on said body member. The faces of the teeth 8 and hence the blades 7 are on lines radiating from the center of the passageway 6. Lock notches 9 are formed in the backs of the teeth 8 of the inner unit midway between the faces thereof. A hub 10 is rigidly secured to the outer fan rotor unit in axial alignment with its passageway 6, extends through the passageway 6 in the inner unit and is mounted on a shaft 11 for the rotor.

In assembling the fan rotor units, the blades 7 of the outer unit are longitudinally aligned with the lock notches 9 and inserted endwise therethrough and between the blades of the inner unit by an axial movement of one of said units in respect to the other.

When the rotor units are assembled, their body members 5 are parallel, in direct contact the one with the other and rigidly connected near their peripheries by spot welding 12, as indicated in Fig. 1. The interlocking engagement, between the blades 7 of the outer fan rotor unit and the lock notches in the inner units thereof, holds said two units against circumferential movement in respect to each other and automatically centers the same with the blades 7 of the outer unit midway between the blades 7 of the inner unit.

The connected body members 5 make a rigid structure, and by assembling two or more units a rotor with the desired number of blades may be readily produced.

The blank from which the inner rotor unit is formed is illustrated in Fig. 4, and it will be noted that the same is produced simply by cutting the periphery of the blank to form the outer longitudinal edges and ends of the blades 7 and by cutting said blank at the inner longitudinal edges of said blades the formation of said unit is completed except the bending of said blades laterally on the folding lines 13. The passageway 6 and lock notches 9 are formed by punching. By thus forming the blades 7 a solid body structure is produced which adds greatly to the rigidity of the rotor.

The blank, from which the outer unit is formed, is identical with the blank shown in Fig. 4 with the exception as to the diameter of the passageway 6.

What I claim is:

A device of the class described comprising substantially duplicate inner and outer units each formed from a single sheet of material, the body members of said units being axially aligned and having toothed peripheries, and blades on the faces of the teeth lying in planes that radiate substantially from the axes of the body members, said inner unit having radial lock notches in the backs of its teeth in which the blades of the outer unit extend and connect the two units against relative turning movement about their axes in either direction.

In testimony whereof I affix my signature.

JULIUS D. HAYNSWORTH.
